James F. Williamson

UNITED STATES PATENT OFFICE.

JAMES E. LAPPEN, OF SELKIRK, MANITOBA, CANADA.

MACHINE FOR SHREDDING AND WASHING FIBROUS STOCK.

1,413,597.

Specification of Letters Patent. Patented Apr. 25, 1922.

Application filed November 5, 1920. Serial No. 422,101.

To all whom it may concern:

Be it known that I, JAMES E. LAPPEN, a citizen of the United States of America, residing at Selkirk, in the Province of Manitoba and Dominion of Canada, have invented certain new and useful Improvements in Machines for Shredding and Washing Fibrous Stock; and I do hereby declare the following to a full, clear, and exact description of the invention, such as will enable others skilled in the art to which it appertains to make and use the same.

My invention has for its object to provide an extremely simple and highly efficient combined shredder and washer, especially adapted for use in shredding and washing with a continuous action, various fibrous stocks or materials, such as partly digested cereal straws, flax, hemp, and the like.

While adapted, as above indicated, for very general use, the improved machine has been especially designed for shredding and washing fibrous stock, consisting of cereal straw and flax or hemp which have first been softened and partly digested.

In practice, I have hitherto made a very cheap, but highly efficient heat insulating board of belt by taking one row, or more of the cereal straws, such as wheat, oat, or barley straw, and the whole stems of flax or hemp thrown in natural condition to a digester, and, by the well known alkali process, have treated these commingled stocks until they were softened up and partially degummed. Hitherto, these commingled and softened and partly degummed fibrous substances, with the commingled shives, would be run through a beating engine and further reduced by a beating action that would tear up the fiber so that the felted heat insulating board made therefrom, while it would be hard, would be very brittle, because of the shortness of the fibers.

My improved shredder is adapted to take this commingled fiber as it comes from the digester, and by a continuous feeding and shredding action, to separate the shives from the fiber, to comb out the fiber without breaking the same to any considerable extent, and to wash out the dirt, leaving the product preferably reduced to about what is known as "half stock," with clean long fibers and commingled shives. In their passage through the improved shredder and washer, the several different kinds of fibrous materials, moreover, will be thoroughly com-

mingled, so that the stronger and the weaker fibers will be quite evenly distributed throughout the fibrous mass.

The improved machine is illustrated in 60 the accompanying drawings wherein like characters indicate like parts throughout the several views. Referring to the drawings:

Fig. 1 is an end elevation of the improved shredder and washer;

Fig. 2 is a vertical section on the line 2—2 of Fig. 1; and

Fig. 3 is a transverse section on the line 3—3 of Fig. 2.

The shell or body member of the machine 70 is in the form of a horizontally disposed cylinder or drum, preferably made up of lower and upper semi-cylindrical sections 4 and 5 connected by hinges 6 at one side and clamped together at their outer sides with 75 water-tight joints, by means of nut-equipped bolts 7, or other suitable devices. The shell section 4 is provided with supporting legs 8, and at its ends, with axially located bearings 9, in which is journaled a drum shaft 80 10. The drum shaft 10, within the shell or casing, carries a shredding drum 11 provided with radially projecting laterally spaced circumferential rows of pins or teeth 12 that are arranged to work between relatively fixed pins or teeth 13 that are secured on the lower shell section 4. At one outer end, the drum shaft 10 is provided with a pulley 14, over which a power-driven belt 85 is adapted to run to rotate the drum. 90

At one end of the shell or casing 4—5, the upper section 5 thereof, in its top, is provided with a receiving hopper, or delivery spout 15; and at the other end of said shell or casing, the lower shell section 4 is provided with a discharge port 16, which, as shown, delivers to a discharge spout 17. 95

On its under surface, the upper shell section 5 is provided with parallel spirally extended blades 18. The toothed drum is to 100 be rotated in the direction of the arrow marked adjacent thereto in Fig. 3, and the spiral trend of the blades 18 is such that under rotation of the drum in the direction stated, the said blades will produce a progressive movement of the fibrous stock from the receiving toward the delivery end of the casing.

For feeding the fibrous stock into the hopper of the casing, I have shown an endless conveyor or elevator belt 19; and for supplying water in a continuous stream to the

casing, I have shown a valve-equipped pipe 20 arranged to deliver also into the hopper. The fibrous stock will therefore be fed continuously into the hopper, will be progressively fed through the casing, and after having been shredded and washed and thoroughly commingled, will be fed continuously out of the casing. While the fibrous stock is being shredded, it will be substantially 10 submerged in water, or, at least, there will be such an amount of water commingled therewith that the shredding or hacking action will take place in the presence of water. The fibrous stock and the water, 15 under the action of the rotary toothed drum, will be caused to rotate within the casing and will be thrown outward by the action of centrifugal force, so that, when moving through the lower portion of the casing, 20 the pins or teeth on the drum and casing will produce the shredding or hacking action, and in moving through the upper section of the casing, the fibrous stock will be thrown against the spiral propelling blade, 25 and, by the latter, given a progressive feed movement toward the delivery end of the casing.

It is further important to note that the inner edges of the propelling blades do not 30 extend concentric to the axis of the casing but extend across the same and across the imaginary cylindrical surface described by the outer points of the pins of the rotary drum, so that the stock will be moved gradually 35 into and gradually out of contact with the edges of said spiral blades. This produces the feeding action without breaking the fiber and without throwing sudden strains on the machine. The propeller 40 blades also serve to assist in straightening out the fibers of the stock in a direction circumferentially of the drum. Obviously, a continuous stream of water running through the casing, and later on, from the fiber, will 45 wash out and carry away the dirt which would otherwise be left in the fiber. Thus a clean fiber stock having long fibers, is produced.

Since the machine operates with a continuous 50 action, it has high capacity. Moreover, it can be driven with comparatively light power, considering the amount of work that it will turn out.

It is, of course, evident that the teeth on 55 the drum, under rotation of the latter, move upward between the propelling blades, so that they throw the stock into contact therewith, but that the teeth or pins do not come into contact with said blades.

60 What I claim is:

1. In a machine of the kind described, the combination with a casing having inlet and discharge passages, said casing within having shredding pins and spiral propelling blades, of a rotary pin-equipped shred-

ding drum working within said casing, the teeth on said casing and drum co-operating to shred the stock, and said propelling blades serving to progressively feed the stock from the delivery toward the receiving passages 70 of said casing.

2. In a machine of the kind described, the combination with a casing having inlet and discharge passages, said casing within having shredding pins and spiral propelling 75 blades, of a rotary pin-equipped shredding drum working within said casing, the teeth on said casing and drum co-operating to shred the stock, and said propelling blades serving to progressively feed the stock from the delivery toward the receiving passages of said casing, the shredding pins of said casing being in the lower portion thereof, and said propelling blades being in the upper portion thereof.

3. In a machine of the kind described, the combination with a casing having inlet and discharge passages, said casing within having shredding pins and spiral propelling 85 blades, of a rotary pin-equipped shredding drum working within said casing, the teeth on said casing and drum co-operating to shred the stock, and said propelling blades serving to progressively feed the stock from the delivery toward the receiving passages of 90 said casing, the inner edges of said propelling blades being extended through the imaginary cylindrical surface described by the outer points of the teeth on said drum, and the teeth on said drum being arranged to move between said propelling blades.

4. In a machine of the kind described, the combination with a casing having inlet and discharge passages, said casing within having shredding pins and spiral propelling 105 blades, of a rotary pin-equipped shredding drum working within said casing, the teeth on said casing and drum co-operating to shred the stock, and said propelling blades serving to progressively feed the stock from the delivery toward the receiving passages of 110 said casing, the shredding pins of said casing being in the lower portion thereof, and said propelling blades being in the upper portion thereof, the inner edges of said propelling blades being extended through the imaginary cylindrical surface described by the outer points of the teeth on said drum, and the teeth on said drum being arranged to move between said propelling 115 blades.

5. In a machine of the kind described, the combination with a casing having inlet and discharge passages, said casing within having shredding pins and spiral propelling 125 blades, of a rotary pin-equipped shredding drum working within said casing, the teeth on said casing and drum co-operating to shred the stock, and said propelling blades serving to progressively feed the stock from 130

the delivery toward the receiving passages of said casing, and means for simultaneously delivering the stock in a stream of water into the inlet passage of said casing.

5 6. In a machine of the kind described, the combination with a casing having inlet and discharge passages, said casing within having shredding pins and spiral propelling blades, of a rotary pin-equipped shredding

10 drum working within said casing, the teeth on said casing and drum co-operating to shred the stock, and said propelling blades

serving to progressively feed the stock from the delivery toward the receiving passages of said casing, and means for simultaneously 15 delivering the stock in a stream of water into the inlet passage of said casing.

In testimony whereof I affix my signature in presence of two witnesses.

JAMES E. LAPPEN.
